CLAIM

The ornamental design for a downspout extension, as shown and described.

DESCRIPTION

FIG. 1 is a front, top perspective view of a downspout extension shown in a disassembled configuration, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1;

FIG. 10 is an enlarged view of detail "10" identified in FIG. 1;

FIG. 11 is an enlarged view of detail "11" identified in FIG. 2;

FIG. 12 is an enlarged view of detail "12" identified in FIG. 2;

FIG. 13 is another front, top perspective view of the downspout extension, shown in a fully assembled configuration; and,

FIG. 14 is a rear, bottom perspective view thereof.

The downspout extension is shown with a symbolic break. The appearance of any portion of the downspout extension between the break lines forms no part of the claimed design. The dashed broken lines in the figures illustrate portions of the downspout extension that form no part of the claimed design. The dash dot dash broken lines in FIGS. 1, 2, 9, 10, 11 and 12 are for the purpose of illustrating the enlarged view indicators and form no part of the claimed design.
